[57] CLAIM

The ornamental design for a nail buffing device, as shown and described.

DESCRIPTION

FIG. 1 is a perspective view of a nail buffing device showing my new design;

FIG. 2 is an exploded perspective view thereof;

FIG. 3 is a front elevational view thereof the side opposite being a mirror image of the side shown except for the appearance of the angled tip;

FIG. 4 is a left side elevational view thereof; the side opposite being a mirror image of the side shown;

FIG. 5 is a top plan view thereof; and,

FIG. 6 is a bottom view thereof.
